UNITED STATES PATENT OFFICE.

BAYARD T. MERRILL, OF ALDERTON, WASHINGTON.

AUTOMOBILE-HEADLIGHT.

1,248,146.

Specification of Letters Patent.

Patented Nov. 27, 1917.

Application filed January 27, 1917. Serial No. 144,945.

To all whom it may concern:

Be it known that I, BAYARD T. MERRILL, a citizen of the United States, and a resident of Alderton, in the county of Pierce and State of Washington, have invented a certain new and useful Improvement in Automobile-Headlights, of which the following is a specification.

My present invention relates generally to headlights, and more particularly to automobile headlights, my object being to provide means whereby all upwardly directed rays may be cut off at certain times and thus all glare eliminated in order to avoid collisions and other accidents ordinarily due to the light blinding of pedestrians and drivers of other automobiles.

In carrying out my invention I preferably provide means supplemental to the usual reflecting surface, and axially disposed light source, whereby when the latter is extinguished, only those rays which are downwardly directed will be given out, so that, while the roadway remains sufficiently lighted, all blinding glare is eliminated.

In the accompanying drawing illustrating the preferred manner in which my invention is carried out—

Figure 1 is a front elevation of my improved headlight, and

Fig. 2 is a vertical section taken therethrough substantially on line 2—2 of Fig. 1.

Referring now to these figures, my improvements contemplate the use of a headlight which, in so far as its general framework, as seen at 10, and its axially disposed lamp bulb 11, are concerned, may be of the usual construction, the lamp bulb 11 being, however, in accordance with my improvements the main source of light, reflected outwardly through the usual lens 12, by means of the reflector 13.

In connection with such a construction, my invention contemplates the provision of a supplemental lamp bulb or light source 14, above the main lamp bulb 11, together with a shield 15 constituted, as shown, by a depending flanged portion of the casing and extending across the upper forward portion of the headlight, in front of the supplemental lamp bulb or light source 14, so as to obstruct the upper portion of the direct rays emanating from the said supplemental lamp bulb.

Furthermore, in accordance with my invention the reflector 13 consists of a plural-

ity of angularly disposed reflecting surfaces 16, 17, and 18, disposed with respect to the supplemental lamp bulb 14 in such manner as to direct all of its rays downwardly. 60

It is obvious, therefore, that when the main lamp 11 is extinguished, all blinding glare will be eliminated and only those downwardly directed rays from the supplemental lamp bulb 14, will emanate from the headlight, including the lower portion of the direct rays of the said supplemental lamp, the upper portion of the direct rays being obstructed by the shield 15 which effectively conceals the lamp bulb or light 70 source 14 from any point in advance of the headlight in line with or above the plane of the lower edge of the said shield.

It is obvious that, in the normal use of the headlight, with the main lamp bulb 11 75 lighted, the supplemental lamp bulb may be either lighted, to be thus ready for use when the main lamp is extinguished, or may be extinguished at the time of the use of the main lamp and lighted simultaneously with 80 the extinguishment of the lamp bulb 11.

I claim:—

1. A headlight having main and supplemental light sources, the latter located above the former, a casing having an opaque portion normally concealing the said supplemental light source and cutting off all horizontal and upwardly extending direct rays therefrom, and reflecting surfaces within the casing common to said main and said supplemental light sources and arranged to direct all reflected rays from the supplemental light source in a downward direction. 85

2. A headlight having main and supplemental light sources, the former of which is substantially centrally located, a casing having an upwardly extended upper rear portion in which said supplemental light source is located above the main source, an opaque 100 shield extending across the upper front portion of the casing and depending below the horizontal plane of the said supplemental light source normally concealing the supplemental light source and cutting off all horizontal and upwardly extending direct rays thereof, and reflecting surfaces within the casing common to said main and supplemental light sources and arranged to direct all reflected rays from the latter in a downward direction. 105

3. A headlight having main and supple-

mental light sources, a casing having an upwardly extended upper portion in which said supplemental light source is located above the main source and having a depending flange forming an opaque shield extending across the upper front portion of the casing normally concealing the supplemental light source and cutting off all horizontal and upwardly extending direct rays therefrom, and angular reflecting surfaces within

the casing adjacent the main and supplemental light sources and arranged with respect to the supplemental light source to direct all reflected rays therefrom in a downward direction.

BAYARD T. MERRILL.
